No Drawing. Application January 25, 1949,
Serial No. 72,756

2 Claims. (Cl. 252—89)

1

This invention relates to a new one-use hand cleaning tablet for individual use and particularly adapted to give a thorough cleaning to soiled or grimy hands. The invention aims to provide a tablet so regulated in composition, structure and method of fabrication that the tablet will be effective in cleaning the hands through attrition and emulsification, will have sufficient strength prior to use so that it will not disintegrate in handling and transportation and yet will readily disintegrate in use when in contact with water and when gently crushed in the hands of the user. Throughout the remainder of this application these two latter characteristics are referred to as "dry strength" and "wet disintegration" respectively.

We are aware that individual cleaning tablets including small pellets or bars of soap, have been heretofore known but these have not been satisfactory products. Further, we are aware that tablets, primarily in the pharmaceutical field, have been adapted to disintegrate rapidly in water, but the techniques used are not feasible in producing a rapidly disintegrable hand cleaning tablet.

Small bars or pellets of soap or non-soap detergents are not satisfactory for individual use because in the normal manufacturing process the product is so dense that the surface exposed to water for effecting solution of the detergent is small, necessitating prolonged rubbing by the user. Penetration of water into the interior of the bar is negligible. During the rubbing the bar is likely to slip from the hands of the user and become lost; moreover, the central portion of the bar is wasted should the user be able to extract sufficient detergent for his hand cleaning requirements. To decrease the density of the bar to the point where rapid disintegration in use occurs is impractical as the product then becomes too fragile prior to use.

In tabletting pharmaceutical products the technique used for effecting rapid disintegration consists of compressing in a mold a granulation to which has been added a small quantity (3 to 5% by weight) of dry starch or similar substance. Upon contact with water the starch swells, breaking apart the tablet granules. Effervescence is also occasionally employed, the escaping gas serving the disintegrating function. To maintain the integrity of pharmaceutical tablets when in the dry state a bonding agent is also added in small quantities (under 10% by weight). The bonding agent is normally of a plastic nature. Bonding agents include gelatin, gum tragacanth, concentrated glycerin or sugar syrups. The quantity of bonding agent is purposely kept as low as possible for reasons which will presently become clear.

In fabricating a rapidly disintegrating hand

10

2

cleaning tablet the techniques employed in the tabletting art are not applicable. The detergents which we have found suitable with regard to their cleaning and emulsifying properties are of a plastic nature, that is, they undergo considerable plastic flow when subjected to the pressures normally used by us in the process of our invention. Moisture content increases the degree of plastic flow during compression. We normally use a granulation which contains approximately 2% moisture. Typical satisfactory detergents used by us are alkyl aryl sodium sulphonates, and cocoanut oil soap.

To produce an effective hand cleaning tablet it is necessary that a significant portion of the composition be a detergent which as previously indicated is of a plastic (flowable under pressure) nature. To produce a hand cleaning tablet in which the active detergent ingredient is less than approximately 10% of the tablet weight, the remainder being a pressure non-flowable and water insoluble filler, is feasible by utilizing established pharmaceutical tabletting methods as previously outlined. Such a tablet however is impractical since the active ingredient is diluted to such a degree that the tablet is cumbersome and ineffective.

We have invented a new and improved one-use hand cleaning tablet and the method of making same in which the proportions of active detergent may be as high as 75% of the weight of the tablet while still maintaining the desirable properties of dry integrity and rapid disintegration in use. The actual percentage of detergent which we use depends primarily upon its activity as a cleaning agent. In general, the non-soap detergents are used in smaller proportions than soap. We have used soap and non-soap detergents together in several formulations. In preparing a granulation for tabletting, we may either mix together the tablet ingredients in the dry state or in the presence of water. In the latter case the material must be dried prior to tabletting.

The following is a preferred composition. The ingredients as listed will produce approximately 100 grams of dry composition:

25 grams sawdust

25 grams alkyl aryl sodium sulphonate

50 grams sodium sulfate

50 0.8 cc. 1% methylene blue solution

1.0 cc. ortho cresol in a mixture of 5 cc. ethyl alcohol and 5 cc. water

The alkyl aryl sodium sulphonate and the sodium sulfate are dissolved in 250 cc. of water and the solution is brought to a boil. The methylene blue is then added. When the solution is clear the sawdust is added and boiling is continued to drive off a part of the water and leave the material in the form of a thick slurry. This is placed

in a shallow pan in a drying oven maintained at a temperature of 110° C. The material is stirred from time to time to prevent caking and the formation of a detergent film on the surface. When the material is dry it is wetted with the ortho cresol solution and again dried. The material is then broken up, and passed through a 10 mesh per inch sieve. The moisture content of the material is brought to approximately 2% by spraying with water and mixing thoroughly. The granulation is then ready for tableting.

Approximately 1.3 grams of material is introduced to a die which is $\frac{5}{8}$ " in diameter with dome faced plungers. The granulation is compressed to 6,500 pounds per square inch. The resulting tablets have a void volume to solid constituent volume ratio of roughly 0.5. These tablets have excellent dry strength, disintegrate readily in use and are extremely effective as hand cleaning agents.

We have used a variety of detergents as the active ingredient in the hand cleaning tablet of our invention. Specifically, the following detergents have been used and are illustrative:

The alkali salts of palmitic, stearic, oleic and linoleic acid. These soaps are present in the wool soap manufactured by Swift & Co.

Sodium lauryl sulfate, an organic alcohol sulfate manufactured by Dupont and sold as Duponol M E Dry.

An alkyl aryl sodium sulphonate manufactured by Monsanto Chemical Co. and sold as Santomerse D.

An alkyl sodium sulphonate manufactured by Dupont and sold as M P 189. Sodium sulfate is incorporated in this product as a diluent.

A sulphonated glyceride ester manufactured by Colgate Palmolive Peet Co. and sold as Arctic Syntex M.

A protein derived detergent manufactured by Kalide Corp. and sold as Lamepon 4C.

Obviously other detergents, for example sulfated or sulfonated amides, sulfated or sulfonated amines and quaternary ammonium compounds may be incorporated in the hand cleaning tablet of our invention to achieve desired characteristics.

In the process of our invention we combine one or more pressure non-flowable and water insoluble solids with the detergent used as active ingredient. This solids material is referred to as the filler. It is desirable that the filler act as an attrition agent when the tablet is in use. Other ingredients are added in relatively small quantities for imparting color, odor, lathering ability and maintenance of moisture content. For purposes of description herein, we have considered as "pressure flowable" a material which coalesces into a homogeneous mass when subjected to a pressure of 6,000 pounds per square inch and as "non-pressure flowable" a material which does not coalesce into or resemble a homogeneous mass when subjected to a pressure of 12,000 pounds per square inch.

As fillers we have used organic and inorganic materials and combinations thereof.

The organic materials used include maple wood sawdust, pine wood sawdust, wood flour, arrowroot starch, corn meal, wheat hulls, ground leather, comminuted paper, cane sugar and sorbitol. Inorganic materials include silica gel, alumina gel, sand, pumice, kieselguhr, sodium carbonate, sodium sulfate and trisodium phosphate. Obviously, other materials may be used for imparting specific features to the final prod-

uct. For example, sodium silicate may be used as a water softening agent.

We prefer to use as a filler a porous hydrophilic solid with a water permeable structure of the ultimate particle. Among the organic fillers, those high in cellulose and/or starch content have particular merit. We have found the following to be highly satisfactory: wood sawdust, wood flour, corn meal, silica gel and alumina gel. Sodium sulfate is a preferred non-porous filler when using sulfated or sulphonated detergents as it is often incorporated as a diluent in commercially available products.

The particle size distribution of the filler is selected in accordance with the degree of attrition desired in the final product. We have found that wood sawdust of screen analysis through 40 and on 48 mesh per inch is satisfactory when mild scrubbing is desired. If gentle action is desired 20 a more finely divided filler is used.

We have discovered the tablet structural conditions which must be fulfilled in order to produce satisfactory hand cleaning tablets in which the percentage of detergent constituent is high.

25 We have also discovered the mathematical expression which relates the percentage plastic constituent in the granulation to the maximum permissible pressure to which the granulation may be subjected in the tableting operation.

30 Higher pressures than those given by the expression will produce tablets which are unsatisfactory as regards wet disintegration in use.

The expression is:

$$P_{\max} = 35,000e^{-2D}$$

35 where—

$P_{\max}$ =the maximum permissible compression pressure in pounds per square inch to produce a satisfactory hand cleaning tablet.

40 D=the fraction by weight of plastic constituent in the tablet. The plastic constituent is normally a detergent.

e is the base of the natural logarithms and has the value 2.72.

45 We prefer to produce tablets in which the amount of detergent is roughly 0.35 of the tablet weight. We find that the expression holds exceedingly well over the range of plastic constituent fractions from 0.125 to 0.75. Tablets containing less than 0.125 detergent are ineffective hand cleaners, while those containing more than 0.75 detergent have the undesirable characteristics of a solid bar or pellet.

55 In developing the mathematical expression referred to a large number of tablets were produced from granulations containing various percentages of plastic constituent. The granulations were prepared by either mixing together the ingredients in finely divided dry form or by preparing a water slurry of the constituents, drying and screening.

Each granulation prepared was compressed in a die at various pressures to produce several tablets. Each tablet so prepared was tested by

60 actually using it for hand washing. The characteristic of wet disintegration was particularly noted. Each tablet was rated as excellent, good, poor and unsatisfactory. The results were plotted and curves drawn for each rating. The plotted results approximate a logarithmic function.

The equation was developed for the unsatisfactory tablet data, since pressures higher than those given by that equation will not be used. The equation developed agrees closely with the 70 experimental results when plotted on semi-log

graph paper. Compression pressures which are greater than those given by the equation yield tablets which do not disintegrate readily. The equation holds over the range from 0.125 to 0.75 detergent. Below 0.125 plastic constituent tablets may be subjected to pressures considerably higher than those given by the equation. For example, tablets containing 0.05 plastic constituent with wood flour as the filler have been compressed to over 50,000 pounds per square inch and were very satisfactory as regards wet disintegration. Compression pressure is not critical at low percentages of plastic constituent and may be varied over wide ranges, while still producing satisfactory tablets. This accounts for the low percentage of plastic constituent normally used in tabletting.

In addition, we have discovered the structure of a hand cleaning tablet which must be realized so that the tablet will have the desirable properties of dry strength and rapid wet disintegration. We have discovered that the voids within the tablet must bear a definite relationship to the volume occupied by solid constituents. We have discovered that the void volume to solid constituent volume ratio cannot be below 0.12 nor greater than 1.8. We prefer to use in our tablets a ratio of roughly 0.5. By void volume we mean that volume of a tablet prior to use not occupied by a solid or liquid constituent. Normally the voids are filled with air which is quickly displaced by water and causes rapid disintegration when the tablet is used.

Experimental data was obtained by preparing a number of granulations and tablets therefrom. The tablets were compressed at various pressures. Flat faced plungers were used in the die. The dimensions of each tablet were measured; and each tablet was weighed. The total volume of the tablet was obtained by calculation. Tablets for each pressure used were subjected to "dry strength" tests and "wet disintegration" tests in use. In these two respects tablets were rated as excellent, good, poor and unsatisfactory. It is to be noted that a tablet rated as unsatisfactory in either respect is not suitable as a hand cleaning tablet. Tablets designated at unsatisfactory as regards "wet disintegration" were, in general, produced at pressures higher than those given by the previously referred to mathematical expression, whereas those rated excellent, good and poor were produced at pressures below that given by the expression.

The determination of voids was accomplished in the following manner. Dependent upon the materials used in a specific tablet composition, a low viscosity liquid was selected in which all constituents were sparingly soluble. For example, it was determined that tablets containing only maple sawdust and Santomerse D, an alkyl aryl sodium sulfonate detergent manufactured by Monsanto Chemical Co., were sparingly soluble in acetone. Prior to use the selected liquid was saturated with the constituents of the tablet. This was accomplished by allowing a large quantity of the constituents to stand in the liquid for several days with occasional stirring. Tablets of each granulation and of each pressure used were then immersed in the selected saturated liquid as prepared above. The liquid was contained in a graduated cylinder. The change in the liquid level in the cylinder then was interpreted as the solid constituent volume of the tablets. In the case of very dense tablets several hours were allowed for penetration of the

liquid throughout the tablet. The void volume and the "ratio" of void volume to solid constituent volume was then obtained by calculation. In certain cases it was possible to check the void volume obtained in the above manner by calculation, utilizing as basic information the densities of constituents obtained from either published sources or our own experimental data.

5 10 The following examples indicate the structural characteristics of a few of the many tablets of various compositions which were prepared.

Example 1

Composition:

1 part (by weight)—alkyl aryl sodium sulphonate
2 parts—sodium sulfate
1 part—pine sawdust

20 The granulation was prepared essentially in accord with the previously outlined procedure. The particle size distribution in the granulation was "through 10 and on 60 mesh."

	Dry Strength	Wet Disintegration	Ratio
25			
Excellent		Excellent	0.502
Do		Poor	0.167
Do		Unsatisfactory	0.099
Poor		Excellent	0.748
Unsatisfactory		do	1.820

Example 2

Composition:

2 parts—alkyl aryl sodium sulphonate
4 parts—sodium sulphate
3 parts—calcium carbonate

35 The granulation was prepared in accord with the outlined procedure. The particle size distribution was "through 10 mesh (0.065" screen opening) and on 60 mesh."

	Dry Strength	Wet Disintegration	Ratio
40			
Excellent		Good	0.433
Do		Unsatisfactory	0.118
Poor		Excellent	0.748
Unsatisfactory		do	1.87

Example 3

Composition:

2 parts—alkyl aryl sodium sulphonate
4 parts—sodium sulfate
3 parts—silica gel

50 The granulation was prepared in accord with the outlined procedure. The particles in the granulation passed through a 10 mesh sieve.

	Dry Strength	Wet Disintegration	Ratio
55			
Good		Good	0.550
Do		Poor	0.294

Example 4

Composition:

1 part—alkyl aryl sodium sulphonate
1 part—coconut oil soap
65 2 parts—sodium sulfate
4 parts—maple sawdust

70 The granulation was prepared in accord with the outlined procedure. The particles in the granulation passed through 10 mesh screening.

	Dry Strength	Wet Disintegration	Ratio
75			
Excellent		Excellent	0.557

Having thus disclosed our invention and described in detail illustrative embodiments thereof, we claim as new and desire to secure by Letters Patent:

1. A dry one-use cleaning tablet having a dry strength sufficient to sustain it against breakage in transit and storage and a void content sufficient to cause it readily to absorb water and rapidly disintegrate in the presence of moisture, consisting essentially of a solid ionic organic detergent and a substantially water insoluble solids filler mixed together and compressed at a pressure of about that given by the expression $P=35,000e^{-2D}$ in which D is the weight fraction of detergent in the tablet and e is the base of the natural logarithms and has the value of 2.72, the detergent being not less than 0.125 and not greater than 0.75 of the tablet weight and the tablet having a gas void volume to solid volume in a ratio of not less than 0.24 and not greater than 0.76, the tablet being readily crushed and disintegrated in the palm of a hand when brought into contact with water.

2. The hand cleaning tablet defined in claim 1

in which the weight of the detergent is between .25 and .50 of the weight of the tablet and the filler comprises a granular cellulose.
